TO UNITED SHOE MACHINERY COMPANY, OF PATERSON, NEW JERSEY, A CORPORA-
TION OF NEW JERSEY.

WAX-THREAD SEWING-MACHINE.

1,249,428.

Specification of Letters Patent. Patented Dec. 11, 1917.

Application filed February 11, 1915. Serial No. 7,463.

To all whom it may concern:

Be it known that we, BERNARD S. LEE and FRED ASHWORTH, citizens of the United States, residing at Beverly, in the county of Essex and State of Massachusetts, have invented certain new and useful Improvements in Wax-Thread Sewing-Machines; and we do hereby declare the following to be a full, clear, and exact description of the invention, such as will enable others skilled in the art to which it appertains to make and use the same.

This invention relates to wax thread sewing machines, and more particularly to heating apparatus for such machines.

In wax thread sewing machines the needle thread, as it comes from the supply, is ordinarily conducted through a receptacle containing melted wax, and then is passed about a series of thread handling devices between the wax receptacle and the work. In order that the thread may reach the work with the wax which has been applied thereto in proper condition to form a satisfactory tight seam, such machines are usually provided with devices for heating the parts of the machine to keep the thread warm from the time that it leaves the wax receptacle until it reaches the work. In lockstitch wax thread sewing machines the wax is usually applied to the bobbin thread before the thread is wound upon the bobbin and the bobbin full of waxed thread is inserted in the rotary hook or shuttle prior to the beginning of the sewing operation. In such machines, heating devices are provided for heating the shuttle and adjacent parts to reduce the wax on the bobbin thread to the proper consistency and to keep the bobbin thread warm so that it will reach the work in proper condition to be incorporated in the seam.

Different heating mediums are employed for heating the parts of wax thread sewing machines, and each particular heating medium requires especially constructed devices for applying the heating medium to the machine. Heretofore it has been the practice to construct different machines for each heating medium, which it might be desirable to use, each machine being especially designed for the particular heating medium to be employed to heat the same.

The primary object of the present invention

is to produce a wax thread sewing machine having a construction such that different heating mediums can be alternatively employed on the same machine for heating the various parts of the machine. In accordance with this object the invention contemplates the provision in a sewing machine of this class of a series of interchangeable heating members especially constructed for the use of different heating mediums, and adapted to fit alternatively at the same point on the machine, which is complementary to each heating member of the series.

Another object of the invention is to provide wax thread sewing machines with an improved heating device for the thread waxing receptacle, by which the wax may be heated in a reliable manner, and maintained at the proper temperature, with a minimum expenditure of heat. In accordance with this object another feature of the invention contemplates the provision of a heating member for the wax receptacle arranged to extend into the receptacle and provided with a series of heat radiating blades or plates for heating the wax along the path of travel of the thread through the receptacle. This member is preferably constructed substantially U-shaped and each arm of the same is formed with radially projecting heat radiating plates. The thread is conducted through the receptacle in a path adjacent the arms of the heating member, so that the wax along the path of the thread is kept in the proper condition to be applied to the thread with a relatively small expenditure of heat. The arms of the heating member are preferably provided with separate electrical heating units which have a resistance control for varying the heat generated in these units.

Another object of the invention is to provide wax thread sewing machines with a system of electrical heating devices by which the machine may be heated efficiently.

Other features of the present invention consist of certain constructions, arrangements and combinations of parts hereinafter described and pointed out in the claims, the advantages of which will be obvious to those skilled in the art from the following description.

In the accompanying drawings, illustrating a sewing machine embodying the various

features of the invention in their preferred forms, Figure 1 is a view in side elevation of a portion of an outsole lock-stitch shoe sewing machine showing the machine 5 equipped with devices for heating the parts of the machine by electricity; Fig. 2 is a view similar to Fig. 1, showing the machine equipped with devices for heating the parts of the machine by steam; Fig. 3 is a plan 10 view, partly in section, of a heating member for the wax receptacle and associated parts forming a part of the electrical heating equipment of the machine, as shown in Fig. 1; Fig. 4 is a view in side elevation, partly 15 in section, and Fig. 5 is a view in front elevation, partly in section, of the parts illustrated in Fig. 3; Fig. 6 is a plan view of a heating member for the wax receptacle and associated parts forming part of the steam 20 heating equipment of the machine, as shown in Fig. 2; Fig. 7 is a view in side elevation, and Fig. 8 is a view in front elevation, of the parts illustrated in Fig. 6; Fig. 9 is a 25 view in front elevation of a steam heating device for the shuttle bracket employed when the machine is equipped as shown in Fig. 2; Fig. 10 is a view in front elevation, and Fig. 11 is a view in side elevation, of a bracket supporting certain of the thread 30 handling devices between the wax receptacle and the work, employed when the machine is equipped with electrical heating devices as shown in Fig. 1; Fig. 12 is a view in side 35 elevation of the bracket illustrated in Figs. 10 and 11, taken from the opposite side of the bracket and showing the thread handling devices associated therewith; Fig. 13 is a view in front elevation, and Fig. 14 is a view in side elevation, of a bracket similar 40 to that illustrated in Figs. 10, 11 and 12, which is employed when the machine is equipped with steam heating devices as shown in Fig. 2; and Fig. 15 is a detail view 45 in side elevation illustrating particularly a portion of the frame of the machine formed to receive interchangeable heating brackets, the outline of one of these brackets being shown in dotted lines.

The sewing machine illustrated in the drawings is a wax thread lock-stitch shoe 50 drawings machine for sewing outsoles to the welts of welted shoes, having substantially the same general construction, arrangement and mode of operation as the machine illustrated and described in the patent granted to Fred Ashworth, one of the present applicants, No. 1,169,909, dated February 1, 1916. The machine comprises an oscillating curved hook needle 40, a curved awl 44, a looper 36, 55 a rotary hook or loop-taker 38 and certain other thread-handling devices hereinafter referred to. The course of the needle thread 60 as it passes from the supply to the sewing point is clearly shown in Figs. 1 and 2. The 65 dry thread as it comes from the supply is

conducted through the wax receptacle 22 and as it emerges from the receptacle, passes through a stripping device 24, and then about a thread truck 12 from which it extends forwardly through an opening or bore 70 16 in the machine frame to the front of the machine. The thread as it emerges from the bore 16, is wound about a tension wheel 26, and from the tension wheel passes through the eyes of a pull-off 28, about the 75 thread truck 31 of the thread locking device, over the thread truck 32 of the auxiliary take-up, then extends downwardly about the thread truck 34 of the main take-up and from the main take-up upwardly through 80 the eye of the looper 36 to the work resting upon the work support 42. The construction, arrangement and mode of operation of the parts of the machine thus far described are substantially the same as the corresponding 85 parts of the machine illustrated in the above Ashworth application. In the present application the machine has been illustrated with a greater part of the mechanism removed in order to give a clearer understanding of the invention.

Wax thread sewing machines of the type illustrated in the drawings are usually heated by constructing and arranging the heating devices to apply the heating medium to 90 the machine to heat the machine at three principal points. The shuttle and associated parts of the machine adjacent the point of operation are heated by applying heat to the bracket or portion of the frame of the machine above the shuttle. To keep the thread warm as it passes from the wax receptacle over the various thread handling devices to the work, the portion of the frame in proximity to these thread handling devices is heated, the heat transmitted thereby being sufficient to keep these devices and the adjacent parts of the machine warm. The wax in the wax receptacle is maintained in a properly melted condition along the path 100 of the thread and the thread is kept warm as it passes from the wax receptacle by means of a bracket extending down into the wax receptacle, to which heat is applied to 105 keep the bracket hot.

The machine illustrated is provided with two sets of interchangeable heating devices constructed and arranged to be fitted alternatively to the machine, one set being specially constructed for the use of electricity 110 as a heating medium, and the other for the use of steam. Each set of heating devices comprises a heating device for heating the shuttle and the adjacent parts of the machine, a heating device for heating the parts 115 of the machine between the wax receptacle and the work, and a heating device for heating the wax receptacle and associated parts. The corresponding heating devices of the two sets are adapted to be applied to the 120

115

120

125

130

frame of the machine interchangeably at the same point on the frame and to this end are given substantially the same shape or contour at the portion thereof which is to be fitted to the frame of the machine, the part of the frame to which the corresponding heating devices are to be alternatively applied being complementary to the corresponding devices. With this construction either of the corresponding heating devices of the two sets may be readily fitted to the frame of the machine and secured in position thereon.

To enable the bracket 46 above the shuttle to be heated this bracket is bored at 68 for the reception of a heating device. When the machine is to be equipped with electrical heating devices as shown in Fig. 1, an electrical resistance unit or cartridge 70 constructed to fit nicely in the bore 68 in the bracket is inserted in this bore. This unit consists of a series of heating coils embedded in insulating material and is provided with terminal wires 71 adapted to be connected in any suitable manner with the main circuit terminals. When the machine is to be equipped with devices for heating the machine by steam as shown in Fig. 2, a steam chamber 72 shown in Fig. 9, having substantially the same cross section as the electrical unit 70, is inserted in the bore 68 in the bracket 46, as shown in Fig. 2 and is supplied with steam through suitable connections with the steam supply system. Both the electrical unit 70 and the steam chamber 72 are arranged to fit closely in the bore 68 in the bracket 46 so that a good contact is formed between the heating device and the bracket to transmit the heat from said device to the bracket. By the heat given off by the heating device applied to this bracket the shuttle is heated so as to reduce the wax on the bobbin thread to the proper condition before it leaves the shuttle, and the devices associated with the shuttle and the parts adjacent the point of operation are kept hot so as to prevent the chilling of the shuttle thread before it reaches the work, and also to keep the needle thread warm. In order to heat the parts of the machine, and particularly the thread handling devices, between the wax pot and the work, interchangeable heating brackets, one constructed for the use of electricity and the other for the use of steam, are provided which are adapted to be fitted to the machine at a point in proximity to these thread handling devices. When the machine is to be heated by electricity the bracket 48 shown in Figs. 10, 11 and 12 is applied to the machine as shown in Fig. 1 to enable the parts of the machine between the wax pot and the work to be kept in a heated condition. This bracket is formed with a bore 74 to receive an electrical resistance unit or car-

tridge 76 similar to the electrical unit 70 and having terminal wires 77 for connection with the main circuit. When the machine is to be heated by steam the bracket 49 shown in Figs. 13 and 14 is applied to the machine as shown in Fig. 2 in place of the bracket illustrated in Figs. 10, 11 and 12. This bracket is provided with a steam chamber 75 arranged for connection with the steam pipes of the steam heating system. The bracket shown in Figs. 10, 11 and 12 and the bracket shown in Figs. 13 and 14 have substantially the same contour at their rear portions where they are fitted to the frame of the machine, so that they are adapted to fit interchangeably into the same complementary recess 91 in the frame of the machine, as shown in Fig. 15. Each of these brackets is provided with a bearing 96 for the shaft 93 of the tension wheel, 85 with a threaded bearing 94 to receive the stud 30 upon which the thread truck 31 of the thread locking device is mounted, with a bearing 92 to receive the shaft 95 of the auxiliary take-up arm, and with a bearing 90 for the reception of the shaft 97 of the main take-up arm, these bearings having substantially the same relations in each of the two brackets. The bearing 92 for the shaft of the auxiliary take-up arm and the bearing 90 for the shaft of the main take-up arm are arranged upon both the brackets 48 and 49 so that when either of these brackets is fitted into the recess 91 in the frame, these bearings will register with the bearings 82 and 98 on the frame for these shafts. Each of the brackets is provided with a bearing 84 to receive a securing screw 85, adapted to be passed through this bearing and screwed into a complementary threaded bearing 87 in the frame of the machine, and with a threaded bearing 86 to receive a securing screw 89, adapted to be passed through a complementary bearing 99 in the frame of the machine and threaded into the bearing 86 in the bracket to secure the brackets alternatively to the frame, the bearings in the frame for the securing screws being arranged to register with the bearings for the screws in each of the brackets. The brackets are both formed with abutments 88 and 82 having the same location on each bracket which are arranged to engage the abutments 80 and 83 on the frame to locate each bracket in the proper position when it is applied to the frame.

In order to enable the wax receptacle to be heated either by electricity or steam the interchangeable brackets shown respectively in Figs. 3, 4 and 5 and in Figs. 6, 7 and 8 are provided. When the machine is to be heated by electricity the bracket 50 illustrated in Figs. 3, 4 and 5 is fitted to the machine as shown in Fig. 1. This bracket is constructed for the reception of a series 130

of electrical resistance units substantially the same as those employed to heat the bracket 46 adjacent the shuttle and the bracket 48 between the wax receptacle and the work. When the machine is to be heated by steam, the bracket 51 shown in Figs. 6, 7 and 8 is fitted to the machine as shown in Fig. 2. This bracket is provided with a steam heating pipe or chamber, arranged to be supplied with steam through suitable connections with the steam heating system. The bracket shown in Figs. 3, 4 and 5 and the bracket shown in Figs. 6, 7 and 8 are each constructed with an upwardly extending plate 102, the forward face of which is formed to fit against an abutment 104 on the frame of the machine, these plates being bored to form bearings 105 to receive securing screws 113. The frame of the machine is provided with threaded bearings 107 which are arranged to register with the bearings 105 in the plate 102 on each of the brackets so that the brackets may be alternatively secured to the frame at the same point by the securing screws.

The bracket shown in Figs. 3, 4 and 5, which is employed when the machine is fitted to be heated by electricity, comprises a cover 100 for the wax receptacle and a U-shaped heating device 106, the arms 108 of which extend through the cover 100 and are secured thereto. The arms of this U-shaped heating device are each formed with a cylindrical chamber 117, as shown in Fig. 5, to receive electrical resistance units 118 having terminal wires 119 for connection with the main circuit terminals. To increase the heat radiating area of the heating device each of the arms of said device are formed with radially projecting heat radiating plates or blades 114 shown particularly in Figs. 4 and 5. This heating device is arranged to extend down into the wax in the wax receptacle and to keep the wax along the path of the thread in a suitably melted condition. The thread as it comes from the supply passes down into the receptacle in a path adjacent one of the arms of the heating device 106, about the thread truck 116 mounted on the lower portion of the heating device which connects the arms thereof and then extends upwardly adjacent the other arm of the heating device through the stripping device 24 and over the thread truck 12 mounted on the cover from which it passes forwardly through the bore 16 in the frame. With this construction of the heating device and with this arrangement of the devices for guiding the thread, the wax in the wax receptacle along the path of the thread is kept in a thoroughly melted condition with a minimum expenditure of heat. To enable the thread to be kept warm after it leaves the stripper 24 until it reaches the bore 16 in the frame, the cover of the wax receptacle

is provided with an upwardly extending arm 122 secured thereto by screws 124 in which is formed a cylindrical chamber 128 to receive an electrical resistance unit or cartridge 132 having terminal wires 133 for connection with the main circuit. The arm 122 is constructed to support the thread truck 12 and a tube 130 through which the thread passes after it leaves the thread truck 12 is mounted on the arm, these parts being maintained in a heated condition by the heat transmitted from the unit 132.

The heating bracket shown in Figs. 6, 7 and 8 employed when the machine is equipped with steam heating devices, comprises a cover 101 for the wax receptacle and a heating device 154 extending through the openings 156 in the cover and secured to the cover by means of a clamping plate 160 held in place by the screw 162. This heating device consists of a U-shaped tube arranged to extend down into the wax in the wax receptacle and to be connected at one end with an inlet pipe and at the other end with an outlet pipe of the steam heating system.

The thread as it comes from the supply passes through an opening 168 in the cover of the wax receptacle down into the receptacle, about a thread truck 164 mounted on a support 166, spanning the arms of the U-tube 154, then extends upwardly through the stripping device 24 and over the thread truck 12, mounted on the arm 170 secured to the cover. The path of the thread through the receptacle is substantially parallel with and adjacent to the U-tube 154 and the wax in the receptacle along the path of the thread is maintained in a properly melted condition by the heat transmitted by the U-tube. Sufficient heat is given off from the U-tube to keep the stripping device 24, the thread truck 12 and the other parts of the machine adjacent the path of the thread as the thread passes from the wax receptacle to the bore 16 in the frame of the machine in a heated condition so as to prevent the chilling of the thread before it enters the bore 16.

When the machine is equipped with electrical heating devices the electrical connections are preferably arranged as shown in Fig. 1. In the construction illustrated in this figure the main current wires are indicated at 56 and are connected through the fuse-box 58 with the main cut-out switch indicated at 60. The main current circuit is connected by the switch 60 with the terminals in the junction box 62 where the current is divided and passes through the various circuits for the resistance units arranged in parallel. The main circuit terminals in the junction box are connected with the resistance unit 70 for heating the shuttle and adjacent parts of the machine by means of the secondary circuit wires or conductors 73 which pass from the junction

box where they are connected with the main circuit terminals, through the tube 79 and are connected with the terminal wires 71 of the resistance unit in the junction block 81 secured to the bracket 46. The main circuit terminals are connected with the heating unit 76 applied to the bracket 48 for heating the tension device, take-up and associated parts between the wax receptacle 10 and the work by means of the secondary circuit wires or conductors 142 passing from the junction box through one of the insulating cables 64 and connected with the terminal wires 77 of the unit 76 within the junction block 78 secured to the bracket 48. The current is conducted from the main circuit terminals in the junction box to each of the heating units 118 inserted in the arms of the heating device 106 by means of the secondary circuit wires or conductors 120 passing from the junction box 62 through one of the insulating cables 64 and connected with the terminal wires 119 of the resistance unit in the junction block 158. It is desirable that the wax in the wax receptacle should be able to be heated up quickly when the machine has been idle for some time and the wax in the receptacle has become hardened throughout. In the practical operation of wax thread sewing machines a great deal of trouble is caused by the wax in the receptacle becoming overheated and boiling over. In order to enable the heat generated in the resistance units 118 to be easily and conveniently controlled a rheostat 66 is connected in series in the circuits of which these units form a part to control the current through each of these units. The provision of the rheostat for controlling the heat generated in the units 118 in the heating device 106 for heating the wax receptacle enables the wax to be heated up and melted quickly when desired and the heat transmitted by the heating device to be conveniently controlled so as to keep the wax in the receptacle in just the right condition to be applied to the thread and to prevent the boiling over of the wax.

The current passes from the main circuit terminals to the resistance unit 132 mounted in the arm 122 on the cover of the wax receptacle through the secondary circuit wires or conductors 134 leading from the junction box through one of the insulating cables 64 and connected with the terminals 133 of said unit in a junction block 136.

The various heating devices with which the machine is fitted when equipped for heating the parts thereof by steam are preferably connected by a system of pipes such as illustrated in Fig. 2. In the system shown in this figure the steam chamber 72 is supplied with steam through an inlet pipe 138 connected with one end of the chamber

by a union 140. The other end of this chamber is connected by a union 143 with an outlet pipe section 144 which extends from the front of the machine rearwardly and downwardly to the back of the machine and is connected by a union 145 with the rear end 70 of a horizontal pipe section 146. The pipe section 146 passes forwardly through a suitable bore in the frame of the machine and has its forward end tapped into the steam chamber 75 in the bracket 49 so that the steam chamber is supplied with steam through this pipe section. The pipe section 146 is located close to the bore 16 in the frame through which the thread passes and the heat transmitted thereby is sufficient to 80 heat the part of the frame adjacent this bore so that the thread is kept warm as it passes through the bore. The steam passes from the steam chamber 75 in the bracket 48 through an outlet pipe section 151 connected 85 with the chamber by a union 150. The outlet pipe section 151 is connected by a horizontal pipe section 152 with the pipe section 153 which in turn is connected with one of the arms of the U-tube 154 and supplies 90 steam thereto. The other arm of the U-tube 154 is fitted with an exhaust pipe 155 through which the exhaust steam passes from the system.

Having explained the nature and object 95 of the invention and having specifically described a machine embodying the various features thereof in their preferred forms, what is claimed is:—

1. A wax thread sewing machine, having 100 in combination, stitch forming devices, a series of interchangeable heating members constructed for the use of different heating mediums and formed to fit alternatively at substantially the same point on the machine 105 which is complemental to all the members of the series, and means for securing said members alternatively in position.

2. A wax thread sewing machine, having 110 in combination, stitch forming devices, a frame for supporting the operative parts of the machine, a series of interchangeable heating brackets constructed to employ different heating mediums and formed to fit alternatively at substantially the same point 115 on the frame which is complemental to all of said brackets and means for securing said brackets alternatively in position.

3. A wax thread sewing machine, having 120 in combination, stitch forming devices, a series of interchangeable heating members constructed to employ different heating mediums and formed to fit alternatively at substantially the same point on the machine 125 which is complemental to all the members of the series, each member of the series having means by which it may be secured in position and securing means complemental

to and arranged to register with the securing means of all of the members of the series.

4. A wax thread sewing machine, having in combination, stitch forming devices, interchangeable heating members constructed respectively for the use of electricity and steam as heating mediums formed to fit alternatively at substantially the same point on the machine which is complementary to both heating members, and means for securing said heating members alternatively in position.

5. A wax thread sewing machine, having in combination, stitch forming devices, a frame for supporting the operative parts of the machine, a series of heating brackets constructed to employ different heating mediums and formed to fit alternatively at substantially the same point on the frame which is complementary to all the heating members, and bearings on said brackets for certain of the operating parts of the machine located in the same relation on all of the brackets of the series.

6. A wax thread sewing machine, having in combination, stitch forming devices, a frame for supporting the operative parts of the machine, a series of heating brackets constructed for the use of different heating mediums and formed to fit alternatively at substantially the same point on the frame; bearings on said brackets for certain of the operating parts of the machine having the same relation upon all of the brackets of the series, each of the brackets having means by which it may be secured to the frame and securing means on the frame complementary to and arranged to register with the securing means on all of the brackets of the series.

7. A wax thread sewing machine, having in combination, a wax receptacle, a heating device arranged to extend into the receptacle and having a series of heat radiating plates extending outwardly from the body thereof, thread guiding means for guiding the thread through the receptacle and means for heating said device.

8. A wax thread sewing machine, having in combination, a wax receptacle, a U-shaped heating member arranged to extend into the receptacle for heating the wax in the receptacle, a series of radiating plates extending from each of the arms of said heating member and thread guiding means for holding the thread in the heat radiating area of the radiating plates.

9. A wax thread sewing machine, having in combination, a wax receptacle, a cover for the receptacle, a heating device attached to the cover and arranged to extend into the receptacle, thread guiding means for guiding the thread through the receptacle, thread

engaging devices engaging the thread after it leaves the receptacle and an auxiliary heating device mounted on the cover for heating said thread engaging devices.

10. A wax thread sewing machine, having in combination, a wax receptacle, a U-shaped heating device arranged to extend into the receptacle having a cylindrical chamber in each arm thereof, an electrical heating unit mounted in each of said chambers, a series of heat radiating plates extending outwardly from each arm of the heating device and thread guiding means for guiding the thread through the receptacle.

11. A wax thread sewing machine, having in combination, a wax receptacle, a heating device arranged to extend into the wax receptacle so as to be partially immersed in the wax, an electrical heating unit mounted in said heating device, circuit connections therefor, means connected in the circuit for said unit to control the heat generated thereby and thread guiding means for guiding the thread through the receptacle.

12. A wax thread sewing machine, having in combination, stitch forming devices, interchangeable heating brackets constructed respectively for the use of electricity and steam as heating mediums formed to fit at substantially the same point on the machine which is complementary to both of said brackets, bearings on said brackets for certain of the operating parts of the machine located in substantially the same relation upon both of the brackets, and means for securing said brackets alternatively in position.

13. A wax thread sewing machine, having in combination, stitch forming devices, a wax receptacle, a series of electrical heating units for heating the parts of the machine to keep the thread warm between the wax receptacle and the work, an electrical heating unit for the wax receptacle, main circuit terminals, conductors for connecting the heating units with the main circuit terminals in parallel, and a rheostat arranged to control the heat generated in the wax receptacle heating unit without affecting the heat generated in the other heating units.

14. A wax thread sewing machine, having in combination, a wax receptacle, a cover for the receptacle, a heating device arranged to extend into the receptacle for heating the wax in the receptacle and a heating device mounted on the cover for keeping the parts of the machine warm along the path of the thread after it leaves the receptacle.

15. A wax thread sewing machine, having in combination, a wax receptacle, a U-shaped heating device arranged to extend into the receptacle and having a chamber in each arm thereof, an electrical heating unit mounted in each of said chambers, circuit connections for the heating units, and thread

guiding devices for guiding the thread through the receptacle.

16. A wax thread sewing machine, having, in combination, a wax receptacle, a heating device arranged to extend into the receptacle so as to be partially immersed in the wax and having a chamber therein, an electrical heating unit mounted in said chamber, circuit connections for the heating unit, and thread guiding devices for guiding the thread through the receptacle.

17. A wax thread sewing machine, having, in combination, a wax receptacle, a heating device arranged to extend into the receptacle, an electrical heating unit mounted in said heating device, thread guiding devices for guiding the thread through the receptacle, a thread guide engaged by the thread

after it leaves the receptacle, an electrical heating unit for heating said thread guide, 20 and circuit connections for the heating units.

18. A wax thread sewing machine, having, in combination, a wax receptacle, a cover for the receptacle, an electrical heating device for heating the wax in the receptacle, thread 25 guiding devices for guiding the thread through the receptacle, and an auxiliary electrical heating device mounted on the cover for keeping of the parts of the machine warm along the path of the thread 30 after it leaves the receptacle.
